UNITED STATES PATENT OFFICE

ABRAHAM WOLF, OF NEW YORK, N. Y., ASSIGNOR TO APOLLO SHIRT COMPANY, OF NEW YORK, N. Y.

COLLAR

Application filed November 14, 1931. Serial No. 575,059.

This invention relates to apparel and more particularly to a collar of the attached type. A collar of the attached type is usually formed with wings and it has been found that attached collars as now constructed have a tendency to curl. In order to overcome this some collars are formed with pockets in the seam along the forward edges of the wing to receive stiffening stays. This has not been found satisfactory as the stays must be removed before a shirt is laundered with the result that the stays are liable to be misplaced when not in use or a person is liable to overlook applying the stays. If the stays are left in the collar when the shirt is sent to a laundry the stays become bent or warped and no longer serve their function in a satisfactory manner.

In other instances, stays are inserted into marginal seams during manufacture of the collars and remain there permanently. This is equally unsatisfactory as the stays are permanently applied to the collars and become bent and warped during laundering of a shirt to such an extent that they do not function in the desired manner.

Therefore, one object of the invention is to provide the collar with a reinforcement for its wings which is formed of fabric and is sewed into the collar along marginal portions of the wings thereby becoming a permanent portion of the collar.

Another object of the invention is to so form the reinforcement that it will stiffen not only the forward edge portion of a collar wing but also the lower edge portion of the wing and thereby very effectively brace the wing and prevent it from curling.

Another object of the invention is to so shape the reinforcement that when it is applied during manufacture of a collar it will not interfere with easy turning of the collar.

The invention is illustrated in the accompanying drawing, wherein:

Figure 1 is a view showing the manner in which the reinforcement is applied during manufacture of the collar.

Figure 2 is a sectional view taken along the line 2-2 of Figure 1.

Figure 3 is a sectional view taken longi-

tudinally of the collar along the line 3-3 of Figure 1.

Figure 4 is a view in elevation showing the collar after it has been turned.

Figure 5 is an enlarged sectional view taken through the turned collar along the line 5-5 of Figure 4.

Figure 6 is a view similar to Figure 5 taken along the line 6-6 of Figure 7.

Figure 7 is a view in elevation of the finished collar, and

Figure 8 is a perspective view of the reinforcement.

The improved collar constituting the subject matter of this invention is of the soft type permanently attached to a shirt and consists of a plurality of plies indicated by the letters "a", "b" and "c", the plies "a" and "b" being the top or outer plies and the ply "c" being an intermediate ply or lining. The lining or intermediate ply is formed of a stiff fabric of the type usually employed for this purpose and the outer plies may be formed of broadcloth or any other soft material desired. These plies are all of the same shape and when the plies are initially assembled the top plies "a" and "b" are placed against each other and then set in place against one face of the lining or intermediate ply as clearly shown in Figures 1 and 2. The assembled plies are then sewed together by a line of stitching which extends in spaced parallel relation to the lower edge of the assembled blanks and end edges thereof.

The wing formed at each end of the collar and indicated in general by the numeral 1 is to have its marginal portions reinforced to prevent curling and in order to do so there has been provided a reinforcing member 2 which may be formed of fabric of the same type used for the lining, or any other fabric that will take stitching. This reinforcing member is substantially V-shaped and has arms 3 and 4 extending rearwardly in diverging relation to each other and conforming to the taper of the collar wing. The forward end of the reinforcing member is cut to form the pointed end 5 and the arm 4 also has a pointed rear end 6. The rear end of the arm 3 is cut to form an inwardly tapered

notch or recess 7. It will be noted that the apex of the tapered end is disposed midway the width of the arm 4 and the inner end of the notch 7 terminates midway the width of the arm 3. Therefore, when the reinforcing member is applied to the assembled blank and placed against the lining "c" the stitching 8 which holds the blanks together may extend axially of the arm 3 and 4 and intersect 10 converging edges of the tapered ends of the arms. While the ends 6 and 7 have been shown one tapered and the other recessed, it will be understood that both may be tapered or recessed or they may be cut square.

15 This reinforcement is so located upon the lining that the apex of its tapered end 5 is spaced rearwardly from the point of the wing 1 of the collar and the stitching extends forwardly beyond the front end of the reinforcement. Therefore, the reinforcement will not interfere with turning of the assembled plies. When this collar is turned, it is folded along the line of stitching and the lining or intermediate ply "c" will be located between 20 the top plies "a" and "b" as shown in Figure 5. Referring to this figure, it will also be seen that the reinforcement will be located within folded marginal portions of the lining and that each arm will be folded upon itself 25 along its longitudinal center. Therefore, the arms of the reinforcement will be of double thickness and add materially to the stiffness of the reinforcement and very effectively prevent wings of a collar from curling.

30 The fact that the pointed ends 5 of the reinforcements terminate in spaced relation to the pointed ends of the wings will eliminate danger of wrinkles being formed in the pointed ends of the wings. After the assembled blanks or plies have been turned a finishing seam 9 extending about margins of the collar is completed by a line of final stitching 10 and a collar will be formed having the appearance of a soft collar of a conventional 35 construction but the wings will be reinforced by fabric stays embedded in marginal portions of the wings as a permanent portion of the collar and serving very effectively to prevent curling. The fact that the free ends 40 of the arms are cut as shown at 6 and 7 will cause these arms when folded to have diagonally extending edges 11 and 12 at their rear ends and the collar will not be marred by 45 ridges formed at ends of the arms 3 and 4 when the collar is ironed.

50 While the reinforcement has been shown V-shaped and formed of a single piece of fabric, it will be understood that it may consist of a pair of fabric strips sewed or otherwise joined together at their converging

ends either before or during manufacture of the collar.

From the foregoing description of the construction of my improved invention, the operation thereof and the method of applying the same to use will be readily understood. It will be seen that I have provided a simple, inexpensive and efficient means for carrying out the objects of the invention.

While I have particularly described the elements best adapted to perform the functions set forth, it is obvious that various changes in form, proportion and in the minor details of construction may be resorted to without departing from the spirit or sacrificing any of the principles of the invention.

Having thus described the invention what is claimed is:

1. A soft collar having end portions extended to form wings tapered towards their free ends, the collar being provided with a bordering seam having portions extending along the lower edges and front edges of the wings, and fabric stays for said wings, 85 each stay consisting of a V-shaped strip of fabric conforming to the taper of the wing and having arms disposed entirely within the seams along the front and lower edges of the wing, the arms having their converging ends integrally united and tapered from opposite side edges to a point spaced from the point of the wing and being folded along their longitudinal centers to provide a stay 90 of double thickness and rear ends of the folded arms being formed with diagonally extending edges.

2. A soft collar having end portions extended to form wings, said collar consisting of outer plies, and a reinforcement for each wing to prevent curling, each reinforcement consisting of a V-shaped strip of fabric placed against the wing-forming portion with its arms extending along marginal portions of the wing and intersecting adjacent the front end thereof, a line of stitching extending along marginal portions of the plies and through arms of the reinforcement axially thereof to secure the plies and reinforcements together, the assembled plies and reinforcements being turned coincident with the line of stitching to dispose the reinforcements in a folded condition between folded marginal portions of the plies, and a line of stitching extending through the turned plies 105 to form a bordering seam for the collar completely enclosing the reinforcement.

In testimony whereof I affix my signature.

ABRAHAM WOLF. 125
